OSCAR CHARLES ROESEN, OF BROOKLYN, NEW YORK, ASSIGNOR TO WOOD NEWSPAPER MACHINERY CORPORATION, OF NEW YORK, N. Y., A CORPORATION OF VIRGINIA

FOLDING MACHINE FOR TABLOID NEWSPAPERS

Application filed December 14, 1927. Serial No. 239,924.

This invention relates to the use of a folding machine for handling tabloid newspaper webs, in which instead of a fold there is a slit along the center line of the half web and the former acts as a pair of angle bars only to lay one sheet over the other with no fold between them.

The principal object of the invention is to provide a construction in which the folding and cutting mechanism is all in one unit adapted to be moved transversely to provide perfect registration between the two split webs from two formers, without the employment of compensating rolls and to avoid 15 puckering of one of the webs under such circumstances.

Other objects and advantages of the invention will appear hereinafter.

Reference is to be had to the accompanying drawing, which is a partly diagrammatic view of the end of a folder showing the formers in elevation and the course of the webs from the formers to the folder.

The web for a tabloid newspaper is slit 25 along the center line of the former so that, where a fold would normally appear along the center of an ordinary web, there is no fold at all but an entire separation of two sheets. Thus the former merely performs 30 the function of two angle bars that will bring together the two halves of the web one upon the other.

These tabloids are run on double width presses necessitating two formers, and the 35 web is slit on the drag roll by three slitters, one slitter between the two formers and the other two slitters at their centers. The formers, of course, deliver to the ordinary folding machine, and it has been customary heretofore to mount this folding machine in stationary position, so that it will be in position to receive the web from one of the formers substantially directly. Now when it is 40 connected up for a tabloid and receives the web from both formers, it will be much out of line with one of them and compensating rolls have been necessary to bring these webs together in proper registration. This resulted often in the puckering of the web that 45 had the longer lead.

This invention is designed to provide for obviating this difficulty, and registering the webs directly without compensating means.

For this purpose, I have shown a construction in which the web comes from the press 55 over the drag roll 10, over which is a slitter 11 at the center dividing the web in the center as usual, and also two other slitters 12 which slit each half web in two and are located in line with the centers of the two formers 13. I have not shown any means for 60 mounting and operating the slitters 11 and 12 as they are mounted on the usual shaft and there is no novelty in that feature.

It is obvious that under these conditions, 65 the center line of the web passing over each former does not produce a fold in the ordinary sense, but the two halves of the web are manipulated exactly as if it were folded along the center line and the two webs are 70 registered with each other back to back between the forming rolls 14 and then pass to the usual nipping rolls 15.

The folder 16 is ordinarily mounted in stationary position as indicated in dotted lines 75 to receive a folded web from the left-hand former and another folder (not shown) is mounted in stationary position to receive the web from the right-hand former, so as to receive the webs most conveniently.

Instead of employing that construction, I mount the transverse folder 16 adjustably by means of screws 17 and poppets 18. Thus it can be moved from the extreme dotted line position, or any position in which it may 85 normally be placed, to a position in which its nipping rolls 19 come exactly half way between the two pairs of nipping rolls 15. The nipping rolls 19 are a part of the folder and are mounted to move with it. In this way the 90 four separate webs, arranged in two pairs, are brought to the nipping rolls 19 exactly in registration with each other. They go through the folding couple, consisting of the folding cylinder 20 and the cutting and collecting cylinder 21, in the usual way without difficulty. This does away with the necessity of placing compensating rolls between the nipping rolls 15 and the nipping rolls 19 to lengthen the path of travel in one case and 95 100

thus bring the webs back into registration with each other.

This not only does away with the compensating rolls, but it eliminates the necessity of adjusting these and keeping them in adjustment. Its particular function is to prevent the puckering of the web that has the longer lead, and thus produce an improved product.

13 I have not illustrated herein the other folder which normally is employed, but that can be made either stationary or adjustable like the folder 16. If stationary, of course, the two folders will be used in the usual way 15 when folding full width webs, and the folder 16 will be used alone when folding the tabloid webs.

Although I have illustrated and described only one form of the invention I am aware of 29 the fact that changes can be made therein by any person skilled in the art without departing from the scope of the invention as expressed in the claims. Therefore, I do not 25 wish to be limited to the exact form shown, but

25 What I do claim is:—

1. In a newspaper printing machine, the combination with a pair of formers, a drag roll, means for slitting the web in two at a 30 point between the two formers, means for slitting each half of the web in two at points registering with the centers of the two formers of a single folder, and means for delivering the four webs from the two formers, 35 to said single folder, and means for adjusting said folder to a point at which its nipping rolls are halfway between the points of delivery from the two formers.

2. In a folding machine, the combination 40 with a plurality of formers and a movable transverse folding mechanism, of means whereby the folding mechanism can be adjusted bodily to compensate and register the webs coming from the formers.

45 3. In a folding machine, the combination of a plurality of formers, means for slitting the webs at the centers of each of said formers, and movable transverse folding mechanism 50 adjustably arranged with respect to the formers in such manner that the margins of the products of the formers shall register when entering the transverse folding mechanism and shall pass directly from the delivery of the formers into the folder.

55 4. In a newspaper printing machine, the combination with a transverse folding mechanism and a plurality of formers, of means for adjusting the folding mechanism sidewise so that several webs from the formers shall 60 pass directly thereto and register with each other on entering the folder.

5. The combination with a former, of a folding mechanism embodying folding cylinders and nipping rolls adapted to 65 cooperate with the former, the entire folding

mechanism being separable bodily from the former.

6. The combination with a former, of a separable self contained folding mechanism movable from one side of the former to the 70 other.

7. The combination with a former, of a separable self contained folding mechanism and means for moving the folding mechanism from one side of the former to the other. 75

In testimony whereof I have hereunto affixed my signature.

OSCAR CHARLES ROESEN.
